ATTORNEY

UNITED STATES PATENT OFFICE.

HOMER A. DOW, OF SALEM, OHIO.

DESIGN FOR A HAT AND COAT HOOK.

49,921.

Specification for Design.

Patented Nov. 21, 1916.

Application filed April 19, 1916. Serial No. 92,329. Term of patent 7 years.

To all whom it may concern:

Be it known that I, HOMER A. Dow, a citizen of the United States, residing at Salem, in the county of Columbiana and State of Ohio, have invented a new, original, and ornamental Design for a Hat and Coat Hook, of which the following is a specification, reference being had to the accompanying drawing, in which the figure is a perspective view of the invention.

I claim:

The ornamental design for a hat and coat hook, as shown.

HOMER A. DOW.

Witnesses:

H. G. Dow,
LOUISE HARWOOD.
